(57) **CLAIM**

The ornamental design for a rotor for electric motor, as shown and described.

DESCRIPTION

FIG. 1 is a front view of a rotor for electric motor showing our new design.

FIG. 2 is a top view thereof.

FIG. 3 is a left side view thereof.

FIG. 4 is a right side view thereof.

FIG. 5 is a cross-sectional view taken along line 5-5 in FIG. 3.

FIG. 6 is a first perspective view thereof; and,

FIG. 7 is a second perspective view thereof.
